UNITED STATES PATENT OFFICE.

ALBERT HAYES, OF NEW YORK, N. Y., ASSIGNOR TO GEORGE F. MCKAY, OF NEWARK, NEW JERSEY; JAMES J. DOYLE ADMINISTRATOR OF GEORGE F. MCKAY, DECEASED.

MECHANICAL MOVEMENT.

Application filed April 18, 1923, Serial No. 632,901. Renewed December 19, 1925.

To all whom it may concern:

Be it known that I, ALBERT HAYES, a citizen of the United States residing in the city of New York, county of New York, and 5 State of New York, have invented certain new and useful Improvements in Mechanical Movements, of which the following is a specification, reference being had to the accompanying drawings, forming a part there- 10 of.

My invention relates to mechanical movements and has for its object to provide a device by which bodies may be given rotary motion of oscillation first in one direction 15 and then in the other overcoming the difficulties due to inertia. A further object of the invention is to provide a device for this purpose which will be simple and inexpensive in construction and will be effective for 20 the purpose intended and not liable to injury.

Where the body to be oscillated is of relatively light weight its oscillation either with or without a step forward in one direction is 25 a comparatively simple matter and devices for this purpose which are effective for the oscillation of such bodies are known. But where the body to be oscillated is very heavy it acquires by rotation in one direction a 30 momentum which cannot be overcome by devices now in use without strain or breakage. By the device of my present invention this difficulty is overcome and the device herein shown and described is adapted for 35 oscillating bodies whether heavy or of light weight without shock or damage of injury to the body itself or to the oscillatory device.

With the objects above indicated and other 40 objects hereinafter described in view my invention consists in the construction and combination of elements hereinafter described and claimed.

Referring to the drawings:

45 Figure 1 is a plan view of the cam disc of my invention.

Figure 2 is a cross sectional view of the disc and the pinion driven by it.

50 In the drawings 1 indicates the driving shaft and 3 indicates a cam disc carried on the driving shaft. 4 indicates a pinion on

the driven shaft 5. The driven shaft is mounted to rotate in a plane at right angles to the plane of the driving shaft and extends across the face of the cam disc on a line near 55 its periphery so that the teeth of the pinion 4 are in position to be engaged by the cam ridges formed on the face of the disc.

On the cam disc are formed cam ridges 6 and 7 having between them a groove 8 adapted to receive a tooth 9 of the pinion 4. The cam ridges 6 and 7 are concentric and are formed on arcs of a circle the centre of which is on line 10—10 passing through the axis of the driving shaft 1 but at a considerable distance from such axis so that these cam ridges are eccentric to the axis of the driving shaft. The cam ridge 6 may form a complete or nearly complete circle though the operative position of it is somewhat less 70 than a half circle. The cam ridge 7 is considerably less in extent than a complete circle and it gradually diminishes in height towards its ends which terminate in the plane of the face of the disc. 75

At the left, as shown in Figure 1, of the cam ridge 6 and concentric therewith is a cam ridge 11 which is separated from cam ridge 6 by a groove adapted to receive a tooth 9 of the pinion 4. This cam ridge 11 80 has its end 13 somewhat below a line drawn at right angles to the line 10—10 through the center from which the arcs of cam ridges 6 and 7 are struck and has its upper end 14 above the plane of the axis of the driving shaft but a considerable distance from the line 10—10. This cam ridge diminishes in height to its ends 13 and 14 to the plane 85 of the face of the disc.

Outside the cam ridge 11 and concentric with it is a cam ridge 16 separated from cam ridge 11 by a groove 19 adapted to receive a tooth 9 of the pinion 4. This cam ridge is wholly above a line drawn at right angles to line 10—10 passing through the axis of 90 the driving shaft, its end 17 being slightly above such a line and its end 18 being substantially on line 10—10. At its ends 17 and 18 this cam ridge diminishes in height to merge with the face of the disc. 95

Outside the cam ridge 16, parallel with it and separated therefrom by a groove 23,

adapted to receive a tooth 9 of the pinion 4, is a cam ridge 20 the end 21 of which is about in line with the end 14 of the cam ridge 11 on a line passing through the center from 5 which the arcs of cam ridges 6 and 7 are struck. At the end 21 this cam ridge diminishes in height to merge with the face of the disc. The other end 22 of this cam ridge is to the right of the line 10—10 and is of full 10 height.

There are thus to the left of the line 10—10, as shown in Figure 1, five cam ridges, 7, 6, 11, 16 and 20.

To the right of line 10—10 outside of cam 15 ridge 6 and concentric therewith, is a cam ridge 26 separated from cam ridge 6 by a groove 27 adapted to receive a tooth 9 of the pinion 4. This cam ridge 26 has its lower end 28 about on a line at right angles 20 to line 10—10 passing through the cam ridge 6 where it is crossed by line 10—10. The upper end 29 is considerably above the axis of the driving shaft and is about on a line at right angles to line 10—10 passing 25 through the end 14 of cam ridge 11. This cam ridge diminishes at its ends 28 and 29 to merge with the plane of the face of the disc.

Outside the cam ridge 26 and concentric 30 therewith is a cam ridge 30 separated from cam ridge 26 by a groove 31 adapted to receive a tooth 9 of the pinion 4. The lower end 33 of this cam ridge is about on a line at right angles to line 10—10 passing 35 through the axis of the driving shaft. At its upper end 34 this cam ridge is of full height and meets and merges with the end 22 of the cam ridge 20 on a line 25—25 which is at an angle of about 25 degrees 40 with line 10—10.

There are thus to the right of line 10—10, as shown in Figure 1, four cam ridges 7, 6, 26 and 30.

As the cam disc is rotated in clock-wise 45 direction starting with a tooth 9 in groove 8 on line 10—10 the tooth is held against rotation until, by reason of the eccentricity of the arc of cam ridges 6 and 7, it is gradually swung inward rotating the pinion 50 slowly. As the end 28 of cam ridge 26 comes in contact with the outside of an adjacent tooth 9 it will force it inward rotating the pinion, the tooth in the groove 8 swinging inward past the end of cam ridge 7. By 55 reason of its eccentricity the cam ridge 26 causes the tooth 9 engaged by it to swing inward rapidly thus rotating the pinion. As the end 33 of cam ridge 30 comes in contact with the next adjacent tooth 9 it causes the 60 pinion to be further rotated, by reason of its eccentricity. As the portion of this cam ridge 30 near its upper end 34 comes into contact with this third tooth it checks its inward swing and gradually brings the 65 pinion to a complete stop.

As the disc continues to rotate the portion of cam ridge 20 near the end 22, at first, holds the tooth against rotating movement and then as the end 18 of cam ridge 16 comes in contact with this tooth the third tooth is 70 swung outward rotating the pinion in reverse direction.

As the disc continues its rotation the second tooth is picked up by the end 14 of cam ridge 11 and the pinion is further rotated 75 in the reverse direction. Further rotation of the disc brings the upper end of cam ridge 6 into contact with the first tooth swinging it outward and bringing the next adjacent tooth into the groove 8. The cam ridge 6 at first acts to continue the outward swing of the tooth engaged by it and thus to continue the rotation of the pinion. As the disc is brought around to its original position the first tooth which, at starting, 80 was in groove 8, will be outside cam ridge 6 the pinion being thus rotated one step further in reverse than it was in the original direction and the pinion will be gradually brought to a full stop as the disc reaches 85 this original position.

All of the cam ridges are on arcs struck from centers eccentric to the axis of the driving shaft. The main portion of each of the cam ridges is formed on an arc though 90 its ends need not be in the line of the arc, except that cam ridges 20 and 30 as they approach their meeting point are not quite on the lines of arcs, being somewhat cut 95 away on their inner faces to avoid too abrupt change from the arc of one to the arc of the other.

The cam ridges are formed with broad bases so as to give great strength in order to overcome without risk or injury, the inertia 100 when a heavy body is to be oscillated and to bring it to a full stop and give it reverse movement without shock. The eccentricity of the cam ridges makes it possible to effect 105 the oscillation of very heavy bodies by the variation in speed of rotation the disc serving by reason of this eccentricity of the cam ridges both as a rotating means and also as a brake.

The disc with its cam ridges may be readily formed by casting without the necessity for machining.

In operation the driving shaft may be rotated continuously in either direction its 110 continuous rotary motion being converted into oscillating movement.

By the construction above described the starting, slowing, stopping and restarting of the pinion 4 is effected by the single operating disc the strain on which is in the direct line through the point of contact of a tooth 9 with the disc and the axis of rotation of the disc. The resistance to the strain of these operations may be made amply sufficient to overcome the inertia of the body to 115 120 125 130

be oscillated however heavy it may be, by making the thickness of the disc such as to give the resistance required.

Having thus described my invention what

5 I claim is:

1. In a mechanical movement for converting continuous rotary motion into oscillating motion, a driving shaft, a driven shaft at right angles to the driving shaft and provided with a pinion, and a cam disc carried by the driving shaft having cam ridges on its face adapted to engage the teeth of the pinion, the cam ridges being formed on arcs concentric one with the other but eccentric to the axis of rotation of the disc.
- 10 2. In a mechanical movement for converting continuous rotary motion into oscillating motion, a driving shaft, a driven shaft at right angles to the driving shaft and provided with a pinion, and a cam disc carried by the driving shaft having cam ridges on its face adapted to engage the teeth of the pinion, the cam ridges being formed on arcs parallel one with the other but eccentric to the axis of rotation of the disc, the number 20 of cam ridges on one side of the median line of the disc being greater in number than the cam ridges on the other side.
- 25 3. In a mechanical movement for converting continuous rotary motion into oscillating motion, a driving shaft, a driven shaft at right angles to the driving shaft and provided with a pinion, and a cam disc carried

by the driving shaft having cam ridges on 35 its face adapted to engage the teeth of the pinion, the cam ridges being formed on arcs concentric one with the other but eccentric to the axis of rotation of the disc, two of 40 said cam ridges extending equally on opposite sides of the median line whereby the driven shaft is slowed, brought to rest and gradually given reverse rotation without shock, the center points of the outer cam ridges at opposite points being out of line. 45

4. In a mechanical movement for converting continuous rotary motion into oscillating motion, a driving shaft, a driven shaft at right angles to the driving shaft and provided with a pinion, and a cam disc carried by the driving shaft having cam ridges on its face adapted to engage the teeth of the pinion, the cam ridges being formed on arcs 50 parallel one with the other but eccentric to the axis of rotation of the disc, the number 55 of cam ridges on one side of the median line of the disc being greater in number than the cam ridges on the other side, two of said cam ridges extending equally on opposite sides of the median line whereby the driven 60 shaft is slowed, brought to rest and gradually given reverse rotation without shock, the center points of the outer cam ridges at opposite points being out of line.

In testimony whereof I hereunto affix my 65 signature.

ALBERT HAYES.
